(57) **CLAIM**

The ornamental design for toothbrush, as shown and described.

DESCRIPTION

FIG. 1 is a front elevation view of my new design for a toothbrush;

FIG. 2 is a rear elevation view thereof;

FIG. 3 is a right side elevation view thereof, the left side being a mirror image thereof;

FIG. 4 is a bottom, right perspective view thereof;

FIG. 5 is a bottom, right perspective view thereof, shown in a partially folded position;

FIG. 6 is a bottom right perspective view thereof, shown in a folded position;

FIG. 7 is a front elevation view of an alternate embodiment of the toothbrush, the only differences being the contrasts in tone and material;

FIG. 8 is rear elevation view of the toothbrush of FIG. 7;

FIG. 9 is a right side elevation view of the toothbrush of FIG. 7, the left side being a mirror image;

FIG. 10 is a bottom, right perspective view of the toothbrush of FIG. 7;

FIG. 11 is a bottom, right perspective view of the toothbrush of FIG. 7 in a partially folded position; and,

FIG. 12 is a bottom right perspective view of the toothbrush of FIG. 7 in a folded position.
